CLAIM

The ornamental design for a handheld transmitter for a pet trainer, as shown and described.

DESCRIPTION

FIG. 1 is a top, right and front perspective view showing our new design for a transmitter for a pet trainer, in a first embodiment.

FIG. 2 is a front elevational view of the transmitter of FIG. 1.

FIG. 3 is a rear elevational view thereof.

FIG. 4 is a right side elevational view thereof.

FIG. 5 is a left side elevational view thereof.

FIG. 6 is a top plan view thereof.

FIG. 7 is a bottom plan view thereof.

FIG. 8 is a top, right and front perspective view showing our new design for a transmitter for a pet trainer, in a second embodiment.

FIG. 9 is a front elevational view of the transmitter of FIG. 8.

FIG. 10 is a rear elevational view thereof.

FIG. 11 is a right side elevational view thereof.

FIG. 12 is a left side elevational view thereof.

FIG. 13 is a top plan view thereof; and,
FIG. 14 is a bottom plan view thereof.

The structural features shown in broken lines have been shown for the purpose of illustrating portions of the transmitter for a pet trainer that form no part of the claimed design.
